UNITED STATES PATENT OFFICE.

CARRODUS BASTOW, OF ALLWOOD, NEW JERSEY, ASSIGNOR TO T. R. GOODLATTE & SONS, (INC.), OF DELAWANNA, NEW JERSEY, A CORPORATION OF NEW JERSEY.

DESIGN FOR A TABLE COVER OR ANALOGOUS ARTICLE.

Application filed November 23, 1925. Serial No. 15,513. Term of patent 3½ years.

To all whom it may concern:

Be it known that I, CARRODUS BASTOW, a citizen of the United States, residing at Allwood, in the county of Passaic and State of New Jersey, have invented a new, original, and ornamental Design for a Table Cover or Analogous Article, of which the following is a specification, reference being had to the accompanying drawing, forming part thereof.

The figure is a plan view of a table-cover, showing my new design, partly in outline, with certain portions in full lines, the parts shown in full lines, with exception of the figure in the center, being repeated in diametrically opposite places in the portion of the design shown in outline.

I claim:

The ornamental design for a table-cover or analogous article, substantially as shown and described.

CARRODUS BASTOW.
